(57) **CLAIM**

The ornamental design for an alarm clock, as shown and described.

DESCRIPTION

FIG. 1 is a bottom view of an alarm clock;

FIG. 2 is a front view thereof;

FIG. 3 is a left side view thereof;

FIG. 4 is a first perspective view thereof;

FIG. 5 is a second perspective view thereof;

FIG. 6 is a rear view thereof;

FIG. 7 is a right view thereof; and,

FIG. 8 is a top view thereof.

The broken lines in the drawings show portions of the alarm clock that form no part of the claimed design.
